UNITED STATES PATENT OFFICE

RALPH L. EVANS, OF NEW YORK, N. Y.

HAIR WAVER

Application filed May 15, 1929. Serial No. 363,261.

The object of my invention is to provide novel features of construction in the hair waver whereby the waver will be lightened, its operation simplified, and its application 5 and removal facilitated, this being very desirable because of the great strain on the scalp due to the many wavers attached to the head at the same time.

A practical embodiment of my invention 10 is represented in the accompanying drawings, in which

Fig. 1 represents the waver with a tress wrapped and secured thereon;

Fig. 2 represents the waver without the 15 tress thereon;

Fig. 3 represents a cross section taken in the plane of the line III—III of Fig. 2, looking in the direction of the arrows, a portion of the shield which surrounds the scalp plate 20 being broken away;

Fig. 4 represents a cross section taken in the plane of the line IV—IV of Fig. 2, looking in the direction of the arrows;

Fig. 5 represents a cross section taken in 25 the plane of the line V—V of Fig. 2, looking in the direction of the arrows;

Fig. 6 represents a cross section taken in the plane of the line VI—VI of Fig. 2, looking in the direction of the arrows;

Fig. 7 represents the waver in longitudinal 30 central section;

Fig. 8 represents a detail view of the waver partly in side elevation and partly in longitudinal central section, showing the parts in the positions they assume when the tube has been drawn outwardly into interlocking engagement with the head of the central rod for the purpose of unscrewing the rod from the scalp plate, and

Fig. 9 represents a detail side view of the waver with the parts in the positions they assume for the application of a tress.

The central rod 1 of the hair waver has a tube 2 mounted thereon for rotary movement in one direction only and also for limited endwise movement on which tube the tress is wound and secured. The outer end of the rod is provided with a head 3 fixedly secured thereto and the inner end of the rod 45 has a tress engaging arm 4 rotatably mounted

thereon. The inner end of the rod also has an axially screw threaded bore 5 which is engaged by a screw 6 which projects outwardly from a scalp member, which, in the present instance, is represented as a plate 55 7, from which scalp plate also projects a tress engaging pin 8 parallel with the screw 6. The swinging arm 4 is brought into and out of coactive relationship with the pin 8 as the rod 1 is screwed inwardly and outwardly. This swinging arm 4 is shown as having a recess 9, adapted to seat the pin 8 therein when brought into coaction therewith.

The scalp plate is preferably imbedded in a shield 10 of yielding heat insulating material, such as soft rubber, for cushioning the device and also for preventing the plate from coming into direct contact with the scalp.

For facilitating the application of the tress to the device, the scalp plate has a flattened edge portion 11 and the shield has a corresponding flattened edge portion 12.

The tube 2 is preferably provided with a gradually tapered inner end portion 13 and an enlarged outer end portion 14, the peripheral surface of which outer end portion may be milled or otherwise roughened, to facilitate the operation of the device.

This tube 2 is free to turn on the rod 1 in one direction but is held against turning on the rod in the opposite direction by a clutch, which, in the present instance, comprises a coil spring 15 surrounding the rod within the bore of a sleeve 16, located within the enlarged outer end portion 14 of the tube and locked thereto by a lug 17 which is located in a slot 18 in the tube. One end of this clutch spring 15 is secured to the sleeve so that when the sleeve and tube are turned in one direction, the coils of the spring will free themselves from the rod and when turned in the other direction, the coils will grip the rod to clutch the sleeve and tube thereto.

Means are provided for yieldingly holding the tube at the limit of its inward sliding movement on the rod with the inner end of the tube in engagement with the circumferential shoulder 19 on the rod, which means is herein shown as comprising an expansion

coil spring 20 surrounding the rod and located between the head 3 at the outer end of the rod and a washer 21 at the outer end of the sleeve 16.

5 The rod and tube may be locked to turn together when the tube is drawn outwardly on the rod against the tension of the spring 20 by providing the head 3 of the rod with one or more lugs 22 and the outer end of the tube with one or more corresponding recesses 23.

In operation:—In applying the waver to the head, the rod 1 is turned in a direction to unscrew the rod from the scalp plate 6 15 sufficiently to permit a tress of hair to be passed between the screw and the scalp plate pin 8. The rod is then turned in the direction to screw the rod toward the scalp plate sufficiently to bring the pin 8 and arm 4 into co- 20 active relationship. The arm is then swung around into engagement with the pin and the tress may then be passed around the arm and also around the tube and secured in this position by any well known or approved 25 means as, for instance, by wrapping a tape 24 around the so coiled tress. The tube may then be rotated on the rod in a direction to tighten the coils of the tress, it being understood that the clutch spring 15 will hold the 30 tress coils in their tightened position by preventing the reverse turning movement of the tube on the rod.

A heating unit of any well known or approved construction (not shown herein) may 35 then be applied to the device for the desired time and then removed.

To remove the device from the tress, the tress is loosened from the tape and rod and the tube is then drawn outwardly along the 40 rod until it is interlocked with the head 3 of the rod by the coaction of the lugs 22 and recesses 23. The tube and rod may then be turned together in a direction which will unscrew the rod from the scalp plate screw and 45 thus permit the removal of the rod and tube therefrom. The scalp plate may then be removed and again connected to the rod for a subsequent operation.

It is evident that various changes may be 50 resorted to in the construction, form and arrangement of the several parts without departing from the spirit and scope of my invention; hence, I do not intend to be limited to the particular embodiment herein shown 55 and described, but what I claim is:—

1. In a hair waver, a scalp member, a rod connected thereto for endwise movement, said scalp member and rod having tress engaging elements arranged to be brought into and out 60 of coactive position by the inward and outward movement of the rod, and a tube mounted for rotary movement on the rod.

2. In a hair waver, a scalp member, a rod connected thereto for endwise movement and 65 a tube mounted for rotary movement on the

rod, said scalp member and rod having a pin and an arm respectively, arranged to be brought into and out of coactive position by the inward and outward movement of the rod.

3. In a hair waver, a scalp member, a rod connected thereto for endwise movement, said scalp member and rod having tress engaging elements arranged to be brought into and out of coactive position by the inward and outward movement of the rod, and a tube mounted for rotary movement on the rod and also for endwise movement along the rod. 70

4. In a hair waver, a scalp member, a rod connected thereto for endwise movement and a tube mounted for rotary movement on the rod and also for endwise movement along the rod, said scalp member and rod having a pin and an arm respectively, arranged to be brought into and out of coactive position by the inward and outward movement of the rod. 75

5. In a hair waver, a scalp member, a rod connected thereto for endwise movement, said scalp member and rod having tress engaging elements arranged to be brought into and out of coactive position by the inward and outward movement of the rod, a tube mounted for rotary movement on the rod in one direction only and also for endwise movement along the rod, and means for locking the tube and rod together for rotary movement in 90 either direction. 95

6. In a hair waver, a scalp member, a rod connected thereto for endwise movement, a tube mounted for rotary movement on the rod in one direction only and also for endwise movement along the rod, and means for locking the tube and rod together for rotary movement in 100 either direction, said scalp member and rod having a pin and an arm respectively, arranged to be brought into and out of coactive position by the inward and outward movement of the rod. 105

7. In a hair waver, a scalp member having a screw projecting therefrom, a rod engaging said screw for endwise movement, said scalp member and rod having tress engaging elements arranged to be brought into and out of coactive position by the inward and outward movement of the rod, and a tube mounted for rotary movement on the rod in one direction only, also for endwise movement along the rod, and means for locking the tube and rod together for rotary movement in 110 either direction. 115

8. In a hair waver, a scalp member having a screw projecting therefrom, a rod engaging said screw for endwise movement and a tube mounted for rotary movement on the rod in one direction only, also for endwise movement along the rod, and means for locking the tube and rod together for rotary movement in either direction, said scalp member and rod having a pin and an arm respectively, arranged to be brought into and out of 120 125 130

coactive position by the inward and outward movement of the rod.

9. In a hair waver, a scalp member having a screw projecting therefrom, a rod engaging said screw for endwise movement, said scalp member and rod having tress engaging elements arranged to be brought into and out of coactive position by the inward and outward movement of the rod, and a tube mounted for rotary movement on said rod.

10. In a hair waver, a scalp member having a screw projecting therefrom, a rod engaging said screw for endwise movement and a tube mounted for rotary movement on said rod, said scalp member and rod having a pin and an arm respectively, arranged to be brought into and out of coactive position by the inward and outward movement of the rod.

20 11. In a hair waver, a scalp member having a screw projecting therefrom, a rod having its inner end engaging said screw for endwise movement on the rod, said scalp member and rod having tress engaging elements arranged to be brought into and out of coactive position by the inward and outward movement of the rod, said rod also having a head at its outer end, a tube rotatably and slidably mounted on said rod, yielding means for holding the tube at the limit of its inward movement along the rod away from said head, coactive means for interlocking the tube and head when the tube is drawn outwardly, and a clutch for permitting rotary movement of the tube on the rod in one direction only.

12. In a hair waver, a scalp member having a screw projecting therefrom, a rod having its inner end engaging said screw for endwise movement on the rod, said rod having a head at its outer end, a tube rotatably and slidably mounted on said rod, yielding means for holding the tube at the limit of its inward movement along the rod away from said head, coactive means for interlocking the tube and head when the tube is drawn outwardly, and a clutch for permitting rotary movement of the tube on the rod in one direction only, said scalp member and rod having a pin and an arm respectively, arranged to be brought into and out of coactive position by the inward and outward movement of the rod.

13. In a hair waver, a scalp member having a screw projecting therefrom, a rod having its inner end engaging said screw for endwise movement on the rod, said scalp member and rod having tress engaging elements arranged to be brought into and out of coactive position by the inward and outward movement of the rod, a tube rotatably mounted on the rod, and means permitting free rotary movement of the tube on the rod in one direction only, comprising a sleeve interlocked with the tube and a coil spring sur-

rounding the rod and having one end secured to said sleeve.

14. In a hair waver, a scalp member having a screw projecting therefrom, a rod having its inner end engaging said screw for endwise movement on the rod, a tube rotatably mounted on the rod, and means permitting free rotary movement of the tube on the rod in one direction only, comprising a sleeve interlocked with the tube and a coil spring surrounding the rod and having one end secured to said sleeve, said scalp member and rod having a pin and an arm respectively, arranged to be brought into and out of coactive position by the inward and outward movement of the rod.

In testimony, that I claim the foregoing as my invention, I have signed my name this 8th day of May, 1929.
